 a corporation of Delaware

Application August 11, 1941, Serial No. 406,307

4 Claims. (Cl. 81—66)

This invention relates generally to pipe tongs of the type employed for making up and breaking out joints of drill pipe and well casing. It is directed particularly to an improved tong embodying a novel safety feature designed to protect the operator from a hazard which may arise under certain circumstances.

In accordance with present-day practice, every rotary well-drilling rig includes as an essential part of its equipment a pair of drill pipe tongs, one right-hand and the other left-hand, for making up and breaking out the tool joints connecting the drill pipe sections. The tongs are suspended in the derrick from counterbalanced lines in order to be capable of vertical adjustment, thus permitting each tong to be applied to either the upper or the lower section of the tool joint. The vertical adjustment also enables the tong applied to the upper tool joint section to move vertically with the joint section as the latter is threaded into or out of engagement with the lower tool joint section.

When making up a joint, it is customary to first spin the joint up reasonably tight by means of a spinning rope wrapped around the upper joint section. The right-hand, or "lead," tong is then applied to the upper joint section and a pull is exerted on the tong lever to make the joint up to the desired degree of tightness, the lower joint section meanwhile being held against rotation by the left-hand, or "break-out," tong. When breaking out a joint, the relative positions of the tongs are reversed—that is, the "break-out" tong is applied to the upper joint section and power is applied thereto, while the "lead" tong grips the lower joint section and serves as a back-up tong to prevent rotation. Tool joint threads have a relatively steep pitch and considerable taper, and consequently when the joint has been broken by approximately a quarter-turn, the unscrewing torque decreases rapidly. It is customary to spin the joint out by rotating the rotary table and the pipe supported thereby in a clock-wise direction, meanwhile leaving the break-out tong clamped to the upper joint section to serve as a back-up tong. It is in connection with the latter practice that a hazard occasionally arises, against which the instant invention was developed as a safeguard.

Rotary tables are seldom if ever equipped with friction braking means, and hence their rotation is not under full control of the driller. When spinning out a joint, the rotation of the table continues for several revolutions after the power has been cut off and after the joint has been broken, due to the inertia of the heavy rotating mass. It will be apparent that if, during the rotation of the rotary table and drill string, the break-out tong should slip down over the rotating lower joint section and grip the joint, serious consequences might result. If the table is rotat-

ing rapidly, the sudden gripping of the tong may sever the tong line and allow the tong to spin around with the pipe, inflicting injury on anyone in the path of the tong lever.

If the tongs are properly counterbalanced and other equipment is in proper operating condition, and if the proper tension is maintained on the relief spring in the drilling hook during the breaking-out operation, the break-out tong should not slip down onto the lower joint. However, the hazard exists so long as it is even remotely possible for the tong to contact and grip the lower joint section while it is rotating. It is not practically feasible to eliminate all possibility of the tong moving downward, but it is possible to deprive this contingency of any serious consequences by preventing the tong from inadvertently gripping the lower joint section.

A principal object of this invention is to provide means whereby a pipe tong is prevented from inadvertently gripping one section of the pipe joint, without interfering with its ability to grip the other joint section.

A further object is to provide a pipe tong embodying adjustable guard means operable, when in one adjusted position, to prevent gripping engagement of the tong with a selected pipe joint section, and adjustable at will into another position wherein it permits gripping of the joint section.

A still further object of the invention is to provide a pipe tong guard which may be quickly and easily applied to existing tongs at the site of operations, without modification of the tong structure.

The manner in which the foregoing and other objects are accomplished will be apparent from the following detailed description of one embodiment of the invention, reference being had to the accompanying drawing wherein:

Fig. 1 is a top plan view of a tong embodying the invention;

Fig. 2 is a view, partly in elevation and partly in vertical section, taken on line II—II of Fig. 1 and illustrating the tong in gripping engagement with the upper section of a tool joint;

Fig. 3 is a plan view generally similar to Fig. 1, but showing the tong in a position wherein the gripping dies are held out of gripping engagement with the joint by the guard means;

Fig. 4 is a view corresponding to Fig. 2 and taken on line IV—IV of Fig. 3, showing the tong in lower position wherein the guard means engage the upper joint section and prevent the dies from gripping the lower joint section;

Fig. 5 is a top plan view of a modified guard construction; and

Fig. 6 is a vertical section taken on line VI—VI of Fig. 5.

Referring to Fig. 1 of the drawing, the novel guard means is shown applied to a left-hand or

"break-out" tong of well-known construction and embodying a pair of inner jaws 11 and 12 pivotally mounted at 13 and 14, respectively, on the inner end of a lever 15, and a pair of outer jaws 16 and 17 pivotally connected by pivot pins 18 and 19 to the outer ends of the respective inner jaws 11 and 12. The outer ends of the outer jaws 16 and 17 are detachably connected by a latch 20 pivotally mounted on one jaw and engaging a latching surface on the other jaw. The pivot pins 13 and 14 are spaced apart longitudinally of the lever 15 whereby swinging movement of the lever in the direction of the arrow P causes the jaws to constrict about the pipe joint and force the gripping dies 21 and 22 mounted in jaws 11 and 12 into gripping engagement with the joint.

The novel guard means provided by the instant invention may comprise a plurality of plates 25 and 26 mounted on the upper side of the tong in a position to normally project substantially radially inwardly into the pipe bore defined by the jaws. It will be observed that the inner edges of the guard plates project farther into the bore than do the teeth of the dies 21 and 22, and hence in order that the jaws may be constricted about the joint sufficiently to cause the dies to grip the joint, it is necessary that the tong be positioned on the pipe substantially as shown in Fig. 2, with the guard plates overlying the upper tool joint section 27.

The guard plates 25 and 26 are preferably mounted on the upper ends of the jaw hinge pins 18 and 19, respectively, and also are preferably, although not necessarily, rigidly secured thereto, as by welding as shown at 28. With this arrangement, the plates may be quickly and easily applied to a tong at the drilling site by the simple expedient of replacing the regular hinge pins by the two special pins with the plates attached thereto.

As was pointed out in the introductory remarks, the left-hand or "break-out" tong must also be capable of application to the lower tool joint section 29 for use as a back-up tong when making up tool joints. For this reason, it is essential that the guard plates 25 and 26 be capable of being rendered inoperative when desired. By mounting the plates on the hinge pins, they may be rotated about the axes of the pins into the dotted-line positions indicated at 25' and 26' in Fig. 1. It is only necessary to loosen the hinge pin retaining nuts 30 sufficiently to permit rotation of the hinge pins, and upon subsequent tightening of the nuts the hinge pins and consequently the guard plates are held in adjusted position by the frictional engagement of the nuts and the plates with the opposite faces of the jaws. If preferred, means may be provided for positively locking the hinge pins and plates in either of two adjusted positions, although I have found from experience that this is not necessary.

It will be observed that the inner edges 31 of the guard plates are arcuate in plan view and are concentric with the axes of the hinge pins on which the plates are mounted. In this manner considerable angular variation in the operative positions of the plates is permissible without changing the extent of inward projection of the plates. It is not essential, however, that the inner edges of the plates be of the above-noted configuration, and this is especially true if the plates are positively locked in predetermined operative position. For example, the edges may be

concave and substantially concentric with the curvature of the pipe.

It is also within the purview of this invention to mount the guard plates on the upper ends of the hinge pins for angular adjustment with respect to the pins, an expedient which would be desirable in applying the invention to tongs in which the hinge pins are held against rotation with respect to one of the jaws. In Figs. 5 and 6 I have illustrated a convenient and inexpensive method of thus mounting the guard plates. The plate 35 is generally similar in shape to the plates 25 and 26 of Fig. 1. The outer portion of the plate, however, is slotted to provide two spaced ears or lugs 36 and 37 which are bored to receive a retaining bolt 38. As shown most clearly in Fig. 6, an arcuate groove 39 is formed circumferentially about the upper portion of the hinge pin 19, to partially receive the retaining bolt 38 and thus lock the guard plate against relative upward movement with respect to the hinge pin, while at the same time permitting the plate to assume any desired angularly adjusted position about the axis of the pin. By tightening the nut 40 on the retaining bolt, the plate may be securely clamped to the hinge pin, the lugs 36 and 37 having sufficient resiliency to permit their flexing to attain this result.

The operation of the guard and the manner in which it performs its intended function will be apparent from a comparison of Figs. 1 and 3 and of their corresponding elevational views shown in Figs. 2 and 4. When withdrawing the string of drill pipe from the well, it is raised by the hoisting mechanism until the joint to be broken is slightly above the rotary table, and the slips are set to support the pipe in the table. The break-out tong is then applied to the upper joint section 27 in the position shown in Fig. 2, and the lead tong is applied to the lower joint section 29 to prevent its rotation while power is applied from the usual automatic cathead to the break-out tong to break the joint by counter-clockwise rotation of the upper joint section. With the break-out tong in the position shown in Fig. 2, the guard plates overlie the upper joint section and have sufficient clearance with the drill pipe to permit the tong jaws to constrict about the joint section 27 and force the dies 21 and 22 into gripping engagement with the joint.

After the joint has been loosened by rotation through approximately a quarter-turn, the lead tong is then removed from the lower joint section and the rotary table is rotated in clockwise direction through the usual drive mechanism. The break-out tong is retained on the upper joint section as a back-up tong to prevent rotation of the stand of pipe being broken out, the tong line extending to the automatic cathead serving as a back-up line. During this operation the friction between the threads of the joint sections transmits sufficient torque from the rotating lower section to the stationary upper section to maintain the tong line taut and the tong jaws constricted about the upper joint. It is obvious, therefore, that during the "spinning out" operation the break-out tong is prevented by the guard plates 25 and 26 from slipping down along the upper joint section and into engagement with the lower joint section.

After the threads of the joint sections are completely disengaged, however, the upper joint section is relieved of the counter-clockwise torque imposed by the spinning lower section, and the only force tending to maintain the tong constrict-

ed about the joint is the weight of the slack tong line. Ordinarily, this is sufficient to prevent the tong from opening up sufficiently to allow the guard plates 25 and 26 to clear the joint section 27 and permit the tong to move downwardly into the position shown in Fig. 4. However, if this should occur, it will be apparent that no harm would result inasmuch as the guard plates would then come into contact with the peripheral surface of the upper joint section 27 and would prevent the tong jaws from constricting sufficiently to permit the dies to contact and grip the spinning lower joint section. This condition is most clearly illustrated in Fig. 3, wherein it will be observed that the dies 21 and 22 are held out of contact with the joint by engagement of the guard plates 25 and 26 with the joint at one side of the dies and by engagement of the heels of the jaws 11 and 12 with the joint at the opposite side of the dies.

It is therefore apparent that if from any cause the break-cut tong should move downwardly around the lower joint while the latter is rotating, the tong dies cannot grip the joint and cause the tong to spin about the axis of the pipe. The frictional contact of the guard plates and the heels of the jaws with the joint is insufficient to exert any substantial torque on the tong.

In addition to the foregoing safety feature, the provision of the guard plates also eliminates the possibility of tong breakage and possible injury to the crew as the result of inadvertently placing the tong on the pipe in too low position. It occasionally happens that the break-out tong is placed on the pipe so low that it overlaps the lower tool joint section, which is also gripped by the lead tong during the initial breaking-out step. If this occurs and the dies in the break-out tong are permitted to grip the lower joint, it is obvious that the two tongs cannot turn relative to each other, and, if the usual amount of power is applied to the break-out tong, one of the tong lines or levers will be broken.

From the foregoing description of one embodiment of the invention and a modification thereof, it will be apparent that a safety device has been provided which is effective in eliminating a hazard which, although of infrequent occurrence, is very likely to cause serious injury to the drilling crew if it does occur.

I claim:

1. A pipe tong for use on sectional pipe joints of greater external diameter than the pipe sections joined thereby, comprising a lever, jaws mounted thereon, a pipe-gripping die in one of said jaws, and a guard member mounted on said tong in a plane above said die and having a portion thereof projecting radially inwardly beyond said die, the projecting portion of said guard member being adapted to normally overlie the pipe joint to permit gripping engagement of said die with the upper pipe joint section, said guard member being so located with respect to said die as to cause said guard member to engage the peripheral surface of the upper pipe joint section and thus prevent gripping engagement of said die with the lower pipe joint section when the tong is in an abnormal lower position, said guard member being adjustably mounted on said tong for adjustment into an inoperative position disposed radially outwardly of the gripping portion of said die.

2. A pipe tong for connecting and disconnecting pipe sections having pipe joints of greater external diameter than the pipe, comprising: a lever, a series of pivotally interconnected jaw segments defining a pipe opening therebetween; means pivotally connecting the end segments of the series to the lever at spaced points thereon, whereby swinging movement of the lever constricts or loosens the segments about a pipe joint positioned in the pipe opening; a gripping die mounted in one of said segments in position to be forced into gripping engagement with the pipe joint upon constriction of the jaw segments; a guard member mounted on said tong and having a portion thereof projecting into said pipe opening radially inwardly of said die and in a plane above said die, the projecting portion of said guard member being adapted to normally overlie said pipe joint and permit said die to engage said pipe joint when the tong is in proper position thereon, said guard member being so located with respect to said die as to cause said guard member to engage the peripheral surface of the pipe joint and prevent gripping engagement of the die therewith when the tong is applied thereto in an improper lower position, said guard member being adjustable at will into an inoperative position wholly outside said pipe opening to permit application of said tong to a pipe joint with the guard member disposed in a plane below the upper extremity of said joint.

3. A pipe tong for use on sectional pipe joints of greater external diameter than the pipe sections joined thereby, comprising a lever, a series of pivotally interconnected jaw segments mounted thereon and defining a pipe opening, hinge pins pivotally interconnecting said segments and said lever, a pair of said hinge pins being disposed on substantially opposite sides of said pipe opening, a gripping die adjacent each of said pair of hinge pins, and a guard member mounted on each of said pair of hinge pins and having portions normally projecting into said pipe opening radially inwardly beyond said dies, the projecting portions of said guard members being adapted to normally overlie the pipe joint to permit gripping engagement of said dies with the upper pipe joint section, said guard members being so located relative to the respective dies as to cause said guard members to engage the peripheral surface of the upper of said pipe joint sections and thus prevent gripping engagement of said dies with the lower pipe joint section when the tong is constricted about the pipe joint in an abnormally low position.

4. A pipe tong for use on sectional pipe joints, comprising a lever, a series of pivotally interconnected jaws mounted thereon and defining a pipe opening, pipe-gripping dies in certain of said jaws, a pair of guard members mounted on said tong on opposite sides of said pipe opening, each of said guard members having a portion thereof projecting into said pipe opening radially inwardly beyond a respective one of said dies, said guard members being so located relative to the respective dies as to cause said guard members to engage the peripheral surface of the pipe joint and thus prevent constriction of the jaws sufficiently to cause said dies to grip the pipe joint when the tong is incorrectly applied to the pipe joint in an abnormally low position.

EDWIN F. CODNER.
